CARBURETOR

Arthur R. Baker, Indianapolis, Ind., assignor, by
mesne assignments, to Columbia Carburetor
Company, a corporation of Delaware

Application September 9, 1932, Serial No. 632,440
Renewed August 22, 1935

9 Claims. (Cl. 261—12)

This invention relates to improvements in carburetors and particularly to means for controlling the fuel mixture in the carburetor. It is filed as a continuation in part of my application, Serial No. 457,362, filed May 29, 1930, which has matured into Patent No. 1,877,117, dated September 13, 1932, and to cover further developments in the carburetor forming the subject matter of said patent.

An object of the invention is to provide a carburetor adapted for use in engines having a high compression.

Referring to the accompanying drawing, which is made a part hereof and on which similar reference characters indicate similar parts,

Figure 1 is a plan view of a portion of a carburetor having my invention applied thereto, Figure 2, a vertical section substantially on line 2—2 of Figure 1,

Figure 3, a section on line 3—3 of Figure 1, Figure 4, a section on line 4—4 of Figure 2, and Figure 5, a section on line 5—5 of Figure 1.

A compression ratio of 4 or 5 to 1 is the normal compression. A 6 to 1 ratio is considered high compression. A 7 to 1 is called super-compression. The carburetor of this application deals primarily with super-compression.

In carburetors now on the market difficulty is experienced with high compression engines. If the engine is operating under exceedingly high compression and the throttle is opened suddenly or to a very great extent a heavy fuel charge will be drawn into the engine which will give a power out of proportion to the demands on the engine, the result of which is that there is a loss of efficiency. By my improved carburetor means are provided for delivering a gradually increasing volume of fuel to the engine and while the volume of the fuel charge is gradually increasing the fuel mixture is enriched and chilled to the point where the excessive charge to the engine is properly conditioned.

In the drawing numeral 10 indicates the carburetor casing which may contain a fuel well and a float chamber of the usual construction. The throttle valve casing 11 contains a sleeve or Venturi valve 12 which may be operated by any suitable mechanism not shown. This valve provides a venturi about a normally fixed cone shaped member 13. Air and gasoline or other fuel are sucked in through and around the tube 14 respectively and delivered under reduced pressure into a hot cap 15 which is positioned in the path of the exhaust gases from the engine 55 whereby it is simultaneously sprayed and heated

to a temperature above that required to fire a normal fuel charge. The fuel and air are so proportioned as to result in a mixture too rich to fire. Surrounding the nozzle arrangement 14 is a spiral 16 which causes the vaporous fuel to travel in a spiral path in contact with the walls of the hot cap. Any drop of liquid fuel which may have formed, will form into a thin film, leak between the periphery of the spirals and the walls of the hot cap and thus become vaporized and pass to a channel 17 and a chamber 18 formed in the upper end of the cone shaped member 13 from the chamber 18. The fuel mixture then passes through radial passages 19 where proper air for combustion is added and then into the chamber 20 from which it is drawn into the suction of the engine. The cone-shaped element 13 has a cylindrical extension 21 which is slidable in a bore in the casing 22. To the lower side of the cone 13 is attached an operating stem 23. In a chamber adjacent the valve arrangement just described is mounted a member 24 within which slides a piston 25. A valve 26 is positioned in the bottom of the chamber 24 through which valve gasoline or other liquid fuel may pass from the space 27 into the space 28 beneath the piston 25. The piston 25 has an arm or bracket 29 secured to its upper end by means of a screw 30, and passes down alongside of the casing and is notched as shown at 31 which notch engages over a lever 32. This lever is pivoted on a pin 33 which is fixed in the casing of the carburetor and extends forwardly and engages a notch at 34 in the side of the sleeve valve 35. The tubular member 24 has an annular groove 36 at its upper end into which groove engage the forks of an operating shaft 37. This shaft is notched at 38 so as to permit the lever 32 to extend through it and is further notched at 39. Into this latter notch engages a bent over or hooked portion 40 depending from the underside of a lever 41. The lever 41 is pivoted at 33 and its free end engages between collars 42 on the stem 23. The piston 25 is provided with an axial bore 43, the upper end of which receives an adjustable screw 44 by means of which screw passage of fluid through the bore is controlled.

As shown in detail in Figure 5 a valve 48 has a depending stem 49 carrying a flange 50 which is engaged by some portion of the sleeve valve 12 as this valve is opened, the valve operating against the tension of a spring 51 which normally tends to hold it closed. As will be apparent the valve 48 is opened upon each opening of the valve 12. Adjacent the valve 48 is another valve

52 which is quite similar in construction having a depending stem 53 which carries a flange 54. The flange 54 is engaged by the lever 41 as this lever is depressed so that the valve 52 is opened 5 each time the stem 23 is depressed as explained more fully above. The valve 52 is urged toward closed position by spring 55. From the structure described it will be apparent that fuel is delivered from the cup or pan 56 into the air stream which 10 goes in through the Venturi tube as the steam 23 is depressed. This enriches the fuel charge. The liquid fuel which passes through the valves 48 and 52 is carried into the Venturi valve through a tube 51. This tube has a small bore 58 through 15 which air is sucked to emulsify and atomize the liquid fuel which is delivered into the main air stream going through the venturi.

In operation the air and liquid fuel are drawn in through and around the tube 14 and sprayed 20 into the hot cap 15. The fuel in this condition contains air with a relatively large volume of liquid fuel at reduced pressure, the combined mixture of which is too rich to be fired. The combined mixture is heated to a temperature 25 above the ignition point of a normal explosive fuel charge in the hot cap 15. As the mixture passes out of the hot cap, it is caused to travel in a spiral path and thus brought into contact with the side 45 of the hot cap which side is toward the exhaust gases which are at a high 30 temperature and thus assist in vaporizing any liquid elements in the fuel charge. When the sleeve valve 35 is depressed by the operator the throttle is opened so that air is drawn in around 35 the conical surfaces 13 and mixed with the fuel charge from the hot cap and delivered to the engine. In carburetors heretofore known depressing the sleeve valve delivered an excessive fuel charge to the engine. Under high compression engines this sudden delivery of an excessive fuel charge was highly objectionable. My 40 improvement consists in providing means for gradually admitting the charge. As the sleeve valve 35 is depressed it pulls down on the lever 32. This lever engages the bracket 29 and depresses the piston 25. The chamber 28 is filled with gasoline which has entered through a channel 46, and through valve 26 into the chamber 28. As the piston 25 is depressed therefore it 45 carries down with it the cylindrical member 24 through the bracket 37 engaging the lever 41 and this depresses the stem 23. The spring 47 allows additional opening of the Venturi valve. As soon as the member 24 has reached the limit of 50 its downward travel it begins to rise as the liquid fuel in chamber 28 is forced out through the port 43. The needle valve 44 controls the rate of escape of this liquid. As the member 24 rises it lifts the stem 23 to open the throttle 55 gradually and thus deliver sufficient air to the fuel charge. While the valve 35 is depressed and the stem 23 is also depressed the suction from the engine through ports 19 creates an increased suction at the nozzle 14. This increases the fuel 60 drawn to the hot cap and further enriches the fuel mixture. The result of this action is to dampen the mixture. The valve stem 23 is automatically lifted so that the air to the engine will gradually increase. This is as it should 65 be. It should be noted that in operating with high compression engines that the fuel charge delivered by my carburetor will be at a much lower temperature than charges delivered by carburetors as now known, in that, the evaporation 70 of the rich fuel mixture will tend to reduce the 75

temperature of the fuel charge. Since the throttle is only partially open the amount of fuel delivered to the engine will likewise be limited.

The compression spring 47 has an important function. This spring is seated in a depression 5 in the casing and bears against the lower side of the lever 41 adjacent the pivot pin 33. The pivot pin 33 enters an elongated slot in the end 10 of the lever 41. The purpose of the spring is as follows:

The liquid fuel in the chamber 28 being non-compressible, the lever 41 fulcrums at point 40 and allows the deflector head 13 to move up and down according to the engine pulsation and to put a substantially uniform suction on the fuel 15 passing through the nozzle 14 and when the throttle valve 12 is depressed, the deflector head 13 is depressed with it through the lever mechanism. Unless there is a cushion it puts too great suction on the nozzle point 14 and enriches the mixture too much. The buffer spring 20 47 is made the right tension to enrichen the mixture entering the motor at that particular throttle opening. It may be found desirable for better refinement in control to provide means for 25 varying the tension of the spring 47.

An analysis of the fuel charge in the hot cap 15 shows the presence of an appreciable amount of non-condensable gas or gases. Present among these gases are carbon monoxide and hydrogen. 30 It is believed the formation of these gases is due to the high temperature to which fuel in the hot cap 15 is raised.

Operating under high compression or super-compression the temperature of this gas will be 35 even much higher than under normal operation or normal compression. The highly inflammable carbon monoxide and hydrogen are dispersed throughout the body of the fuel and serve to conduct the ignition flame through the fuel 40 charge.

It will be obvious to those skilled in the art that various changes may be made in my device without departing from the spirit of the invention and therefore I do not limit myself to 45 what is shown in the drawing and described in the specification, but only as indicated by the appended claims.

I claim:—

1. In a carburetor having means for mixing 50 the liquid fuel and air to form a mixture which is too rich to fire, a valve for controlling admission of air to said mixture, said valve comprising two movable elements, one movable relative to the other, and means for moving both of said 55 elements at the initial opening of the valve but for stopping movement of one of said elements after the valve has moved to an open position, substantially as set forth.

2. A carburetor having means for mixing and simultaneously heating liquid fuel and cold air to 60 create a fuel mixture too rich to fire, a valve for admitting air to said mixture, means for operating said valve, and means for delaying opening of the valve to gradually increase the supply of cold air to said mixture when the manually operable means is operated, substantially as set forth.

3. Means for preparing a proper fuel charge for an internal combustion engine comprising means for mixing and atomizing liquid fuel and air and simultaneously forming a mixture which is too 70 rich to fire and heating the mixture to a temperature above the ignition point of a normal explosive fuel charge, a valve for supplying air to said fuel charge and for gradually controlling the 75

increase of the supply of air automatically and simultaneously adding to the supply of air a predetermined amount of atomized liquid fuel, substantially as set forth.

- 5 4. A carburetor adapted to supply a non-detonating charge to an internal combustion engine operating under super-compression comprising means for mixing cold air and fuel to form a mixture too rich to fire, simultaneously
10 heating the mixture to a temperature above the ignition point of a normally explosive charge, and means for supplying conditioning air to the fuel charge and means for supplying the fuel charge gradually as the throttle valve is open,
15 and means for supplying atomized liquid fuel to the air to further enrich the air in fuel as it is supplied to the rich, highly heated fuel charge previously prepared, substantially as set forth.
20 5. In a carburetor having means for mixing fuel and air to form a mixture too rich to fire, means for heating said mixture to a temperature at which an explosive charge would be ignited, a valve for controlling the admission of
25 air to said rich mixture to create a fuel charge of the desired richness, and means for limiting operation of said valve to effect a gradual addition of air to the said fuel mixture, and means operable by said valve for supplying an additional
30 volume of fuel to further enrich the fuel charge, substantially as set forth.

6. In a carburetor having means for mixing fuel and air to form a mixture too rich to fire, means for heating said mixture to a temperature
35 at which an explosive charge would be ignited, a valve for controlling the admission of air to said rich mixture to create a fuel charge of the desired richness, means for limiting operation of

said valve to effect a gradual addition of air to the said fuel mixture, means operable by said valve for supplying an additional volume of fuel to further enrich the fuel charge, and means for absorbing impulses of the engine to prevent fluctuations in the said valves thereby maintaining the fuel and air supply of a relatively even flow, substantially as set forth.

5 7. In a carburetor having means for mixing liquid fuel and air to form a rich mixture, a valve for controlling admission of air to said mixture, said valve comprising a valve disk and a valve seat, means for moving the valve disk and valve seat at the initial opening of the valve but for moving the valve disk relative to the valve seat
10 15 to completely open the valve.

8. In a carburetor having means for mixing fuel and air to form a rich mixture, a valve for controlling the admission of air to said fuel mixture to create a mixture of the desired richness, means for supplying additional fuel to the air to enrich the mixture and means for absorbing impulses from the engine of the vehicle to insure a relatively even flow of the fuel.

20 9. In a carburetor having means for mixing liquid fuel and air to form a rich mixture, a valve for adding air to said mixture, said valve comprising two movable elements, one movable relative to the other, the space between the elements determining the extent of opening of the valve, both of said elements being movable at the beginning of opening of the valve and means for restoring one of the elements to its initial position after a predetermined period after movement
25 30 35 of the elements together.

ARTHUR R. BAKER.
